UNITED STATES PATENT OFFICE.

JOHN M. CASE, OF COLUMBUS, OHIO, ASSIGNOR TO THE CASE MANUFACTURING COMPANY, OF SAME PLACE.

GRADUAL-REDUCTION MACHINE FOR MILLING.

SPECIFICATION forming part of Letters Patent No. 297,759, dated April 29, 1884.

Application filed May 31, 1883. (No model.)

To all whom it may concern:

Be it known that I, JOHN M. CASE, a citizen of the United States, residing at Columbus, in the State of Ohio, have invented an Improvement in Gradual-Reduction Machines for Milling, of which the following is a specification.

My invention relates to that class of grain-reduction machines where a series of rolls are arranged in one common frame and combined in such a manner that the several reductions and separations of the material are made in one common machine. The machine is constructed with a series of vertical rolls corrugated in the usual manner and combined in one common frame. The frame containing the bearings of the rolls is constructed of iron. To this iron frame I bolt a wooden frame, to which frame are attached wooden boards for inclosing the screens. By this construction I am enabled to make a machine of any desired length and any desired screening capacity by simply building onto the iron frame the wooden extension of a length sufficient to receive the required screening apparatus. Ordinarily I make the screens about seven feet long; but they may be much longer or shorter. At the end of the wooden inclosure I construct a vertical discharge-chamber, which is common to all the several screens or riddles, the object of this discharge-chamber being to conduct the material to any desired point in the mill; or, as I prefer, it may be connected to a suction-fan, which suction-fan may be used both for the purpose of elevating the material and also producing a separation of the stock, thus taking out much of the fibrous and impure material. In this system of elevation and purification of the stock I use dust-catchers and settling-chambers, as represented in my application for patent for atmospheric elevators for bolts of even date herewith, Serial No. 96,702. In my present machine I use one shaking screen for each reduction, and also a return conveyer-board, which is so arranged as to cause the material, after being sifted, to be carried back to the next reduction. The several rolls are driven by one endless belt on each side of the machine, the belt driving the

fast rolls being on one side and that driving 50 - the slow rolls on the other side. The belt which drives the slow rolls I usually cross, while the belt which drives the fast rolls is a straight belt. The tightening device is so arranged that one common lever on each side of 55 the machine operates a series of tightening-pulleys, and by a slight movement of the lever the belt may be loosened, so as to cause the machine to stop, or by tightening it the machine may be put in operation. The construction of the bearings of the rolls, the means of opening and closing the rolls, and for leveling is the same as that I use in my four-roller mill, for which invention I have made application for patent of even date herewith, Serial No. 96,699. The flow of the material over the screens and the return of the material after being sifted to the next rolls are accomplished by the use of reverse hangers, which are supported in disks or plates having circular slots, in such a manner that the stock may be caused to travel down the riddle and return with whatever degree of rapidity the miller may desire. The returning-boards beneath the screens are supported by links or 70 hangers suspended from the same slotted disks, but in reverse positions to those which support the riddles or screens above. This causes the material to pass backward to the next successive pair of rolls. The hangers consist of 75 links loosely pivoted to the screens and return-boards, respectively, and having at their upper ends wrist-pins which pass through circular slots in the disks. When all the pins are in the lower extremities of the slots, the sieves 80 and boards will be horizontal, or nearly so. Consequently the progress of the material from the receiving to the delivering ends will be less rapid than when the hangers at the receiving ends occupy positions nearer the 85 summits of the slots. A reversal of this effect may be produced by elevating the hangers at the delivery ends. I employ a shaking device by means of which I operate the whole series of riddles and return-boards by one common eccentric shaft and eccentric band. This shaking device is so constructed as to balance 90 the momentum of the several riddles giving 95
